GAME TABLE

Vincent E. Brotherton, Van Nuys, Calif.

Application October 27, 1952, Serial No. 22,001

Term of patent 7 years

(Cl. D34—5)

To all whom it may concern:

Be it known that I, Vincent E. Brotherton, a citizen of the United States of America, residing at Van Nuys, in the county of Los Angeles, State of California, have invented a new, original, and ornamental Design for a Game Table, of which the following is a specification, reference being had to the accompanying drawing, forming a part hereof.

Figure 1 is a front oblique perspective view of a game table showing my new design;

Figure 2 is a side elevational view of the table of Figure 1;

Figure 3 is a front elevational view thereof;

Figure 4 is a top plan view thereof; and

Figure 5 is a fragmentary top oblique view of a rearward portion of the top of the table shown in Figure 4.

The side opposite that shown in Figure 3 is substantially plain.

I claim:

The ornamental design for a game table, as shown and described.

VINCENT E. BROTHERTON.
